UNITED STATES PATENT OFFICE.

JUDSON SHOECRAFT, OF ESKRIDGE, KANSAS.

ABSOLUTE AND PERMISSIVE BLOCK-SIGNALING.

1,229,155.

Specification of Letters Patent.

Patented June 5, 1917.

Application filed June 24, 1916. Serial No. 105,593.

To all whom it may concern:

Be it known that I, JUDSON SHOECRAFT, a citizen of the United States, residing at Eskridge, in the county of Wabaunsee and State of Kansas, have invented new and useful Improvements in Absolute and Permissive Block-Signaling, of which the following is a specification.

This invention relates to improvements in block signal systems for railways and has particular application to a single signal system for use on single track railways provided with sidings.

In carrying out the present invention, it is my purpose to provide a block signal system which will be found especially useful on single track railways provided with sidings and whereby a train traversing the trackway and approaching the siding may cause a danger signal to be displayed at the siding when an opposing train enters the vicinity of the siding, thereby holding the opposing train beyond the siding so that the approaching train may enter the siding, and whereby opposing trains approaching each other on the trackway will be given absolute stop signals, while following trains will be given permissive signals so that the rear train may follow the leading train from block to block.

It is also my purpose to provide an interlocking block signal system for single track railways whereby a train in one block may when leaving such block and entering the next block, cause a danger signal to be displayed and lock the signal in danger position, while traveling through the last-named block so that the engineer of a following train will be advised as to the condition of the block ahead.

A further object of my invention is to provide an interlocking block signal system for single track railways wherein each signal motor will be under the control of two control circuits that are under the control of an interlocking relay which, in turn, is controlled by the presence of trains in the blocks and wherein a train in one block will break one control circuit of the particular signal motor by deenergizing the corresponding side of the interlocking relay, and then break the other control circuit when entering the next adjacent block and hold the first-mentioned circuit open so that the danger signal will be displayed, this

breaking of the control circuits and holding thereof in open position being due to the armature of the last deenergized side overlapping the armature of the first deenergized side of the interlocking relay and holding the first armature down irrespective of the reenergization of the magnet of the first side of the interlocking relay; and wherein either side of the interlocking relay may hold the other side in circuit opening position, depending upon which side of the interlocking relay is deenergized first.

With the above and other objects in view, the invention consists in the construction, combination and arrangement of parts hereinafter set forth in and falling within the scope of the claims.

In the accompanying drawings;

Figures 1 and 1^a when taken together show diagrammatically the circuit connections between the blocks between the sidings and illustrate the positions of the semaphores when the blocks between the sidings are occupied by trains moving in the same direction.

Figs. 2 and 2^a when taken together show the same circuit connections and the positions of the semaphores when two trains approach each other head on and one train follows another.

Figs. 3 and 3^a taken together illustrate the positions of the semaphores when one train is following another and the leading train has set the signals against the following train.

Fig. 4 is a view in side elevation of one of the interlocking relays.

Fig. 5 is a top plan view of the same.

Referring now to the drawings in detail, 10 and 11 indicate the parallel lines of rails of a trackway and this trackway is divided into blocks A, B, C, D, E, etc., by means of suitable insulation 12 arranged between the lines of rails at the meeting ends of the blocks to insulate the rails of one block from those of adjoining blocks. Located at the meeting ends of the blocks are semaphores, each embodying a signal blade 13 normally held in clear position and adapted to gravitate to danger position, and a motor 14 connected to the signal blade 13 through suitable mechanism and adapted, when energized, to hold the signal blade at clear and to release the signal blade, when deenergized, so that such blade may move to a po-

sition indicative of danger. Also located at the meeting ends of the blocks are interlocking relays each embodying, in the present instance, a base 15 preferably, although not necessarily, formed of insulating material and equipped with upwardly extending supports 16 adjacent to the respective ends thereof having the upper extremities bent toward each other as at 17 and lying in a horizontal plane. Secured to the under sides of the horizontal end portions 17 of the respective standards are electro-magnets 18 and 19. Mounted upon the base 15 adjacent to the respective ends thereof are pivot posts 20 and pivoted upon the respective posts 20 at each end of the base are contact levers 21, 22 and 23. Extending across the upper edges of the respective sets of levers 21, 22 and 23 and insulated from such levers are armatures 24 disposed within the influence of the poles of the magnets 18 and 19 respectively. Arranged above the contact levers 21 and 23 respectively are contacts 25 and 26, while arranged below the contact lever 22 is a contact 27. The terminals of the magnets 18 and 19 are connected across the lines of rails of adjoining blocks at the meeting ends of such blocks and also connected across the lines of rails of each block 30 is a source of energy as a battery 28. Each motor 14 is under the control of two circuits, one circuit including a conductor 29 leading from one side of the motor 14 and connected to one side of a common battery 30, a conductor 31 leading from the other side of the battery 30 and terminally connected with the contact lever 23 under the control of the magnet 19, and a conductor 32 having one end connected to the contact 26 coöperating with the lever 23 and the other terminal connected to the other side of the motor 14; and the other circuit including a conductor 33 tapped onto the conductor 32 and terminally connected to the contact 26 coöperating with the contact lever 23 under the influence of the magnet 18, and a conductor 34 having one end connected to the lever 23 under the influence of the magnet 18 and the other end terminally connected to the conductor 31.

Under normal conditions, that is, when the blocks are unoccupied, the relay magnets 18 and 19 are energized from the respective track batteries, thereby holding the armatures and contact levers elevated and as long as the contact levers 23 are elevated, such levers engage the contact 26 and hold both control circuits of the respective motors energized so that the signal blades will be held in clear position.

Certain of the blocks, in the present instance, the blocks A and E, communicate with the sidings S, S respectively, and the respective lines of rails of the sidings adjacent to the switch points are electrically con-

nected to the lines of rails of the trackway and these portions of the rails are insulated from the remaining portions, as at 35, so that a train upon the siding in the vicinity of the switch points will have the same effect upon the relays as a train in the block on the trackway.

In accordance with my present invention, the inner ends of the contact levers 21 of each interlocking relay are relatively long so that the end of one lever will overlap the end of the other lever when both sets of levers are relieved of the influence of the respective magnets so that the lowermost set of levers may be held down by the other set irrespective of the reenergization of the relay magnet of the bottom set, this locking of the contact levers in lowered position constituting the interlocking feature of the relay.

Located in the advance motor circuit of the set adjacent to each siding, that is, the motor control circuit in advance of the switch points of the siding, is an auxiliary relay 36 embodying an electro-magnet 37 and an armature 38 disposed within the influence of the pole of the magnet 37 and connected to one side of the particular control circuit and normally held in engagement with a contact 39 connected to the other side of the control circuit to maintain the particular control circuit closed at this point. The magnets of these auxiliary relays are connected in controlling circuits respectively and the circuits of the auxiliary relays extend through the interlocking relays of the blocks between the sidings and are so arranged that as long as a train is approaching one of the siding switches, the auxiliary relay ahead of such train will be held deenergized in order to break one of the controlling circuits of the motor of the signal at such siding so that when an opposing train approaches the siding switch and breaks the other control circuit of the signal motor the signal will gravitate to danger so as to display a danger indication to the engineer of the train. On the other hand, these circuits are so arranged that the train approaching the siding switch holds the auxiliary relay behind it energized so that the following train will not receive a danger signal until such train enters the block immediately behind the preceding train and when the following train has entered the block behind the leading train it finds a danger signal, incident to the interlocking relays having been deenergized by the preceding train passing from one block to the other, as more fully described hereinafter.

As will be seen, upon reference to the drawings, the auxiliary relay magnet 37 at the block D has one terminal connected by way of a conductor 40 with a common wire 41 that extends 130

throughout the length of the concerned section of the trackway and has the opposite terminals connected with sources of energy, as batteries, 41' and 42 respectively located 5 adjacent to the sidings. The other terminal of the relay magnet 37 at block D is connected with one terminal of a conductor 43 that extends through the contacts 25 and the contact levers 21 under the control of the magnets 18 and this conductor 43 is connected to the other side of the battery 41'. The auxiliary relay magnet 37 adjacent to block B has one terminal connected with the common wire 41 by means of a conductor 44 and the other terminal connected with one end of a conductor 45 that extends through the contacts 25 and the contact levers 21 under the control of the magnets 19 of blocks C, D, and E and is terminally 10 connected to the other side of the battery 42. By means of these connections, it will be seen that as long as all of the duplex relays are energized, the auxiliary relay magnets 37 will be energized and the respective control circuits held closed at these 15 points. For instance, current for the relay 36 at block D will flow from one side of the battery 41', through the conductor 43 and the contact levers 21 and contact 25 therein, the magnet of the relay 36 and then back to the other side of the battery 41' by way of the conductor 40 and the common wire 41, while current for the auxiliary relay magnet at block B will flow from one 20 side of the battery 42, through the conductor 45, and the contact levers 21 and contacts 25 therein, the relay magnets 37 and then back to the battery 42 by way of the conductor 44 and the common wire 41. 25 At each interlocking relay, the conductor 45 is tapped onto the contact 27 coöperating with the contact lever 22 under the control of the magnet 18, by means of a branch wire 46, while the conductor 43, at each 30 interlocking relay, is connected with the back contact 27 coöperating with the lever 22 under the control of the magnet 19, as clearly shown in Figs. 1 and 2 of the drawings.

35 In operation, a train when passing from block to block, for instance, from block C to block B, as illustrated in Fig. 1 of the drawings, will short circuit both magnets 18 and 19 of the interlocking relay at the 40 meeting ends of the blocks B and C, thereby breaking both control circuits of the motor 14 so that the signal blade may gravitate to danger position. When the train is in block C, the interlocking relay magnet 19 is deenergized and the armatures drop, thereby breaking one control circuit of the motor and as the train passes from block C across the insulation into block B, the magnet 18 of the interlocking relay is deenergized and the armature lever 21 drops

down onto the adjacent end of the armature lever 21 under the control of the magnet 19, thereby locking the first broken circuit of the motor 14 open so that the first circuit will remain open while the second circuit is open, thereby causing the danger signal to be displayed behind the train so that a following train entering block C, as illustrated in Fig. 1*, will receive a danger signal. Should two trains enter adjacent 75 blocks simultaneously, either following each other, or approaching each other, the danger signal will be displayed at the meeting ends of the blocks, incident to both control circuits of the signal motor being broken 80 by the short circuiting of the magnet of the interlocking relay.

When a train enters a block adjacent to one siding, as, for instance, block A in Fig. 2, the magnet 19 of the interlocking relay 85 is deenergized, thereby dropping the contact levers and upon the downward movement of the contact lever 21, the circuit of the magnet 37 of the auxiliary relay adjacent to the other siding is broken, thereby de- 90 energizing such other relay and opening the particular control circuit of the signal motor, as shown in Fig. 2*. Should a train enter the block E, as shown in Fig. 2*, the other control circuit of the signal motor will be 95 broken, as illustrated, incident to the short circuiting of the track battery and the deenergizing of the magnet 19 of the interlocking relay. Thus, both of the control circuits of the signal motor are broken and the train 100 in block E given a danger signal. However, should the train passing through block A continue on to block E, as illustrated in Figs. 3 and 3* of the drawings, the circuit of the magnet 37 of the auxiliary relay 36 at 105 block D will be held open as the train proceeds from block to block, incident to the short circuiting of the track batteries and the deenergizing of the interlocking relays so that whenever a train enters block E before the train passing from block A has 110 reached the siding, a danger signal will be displayed. On the other hand, the auxiliary relay magnet at block B is maintained energized during the travel of the train from 115 block A to block E, incident to the armature levers or contact levers 22 under the control of the magnets 18 dropping onto the back contacts 27, thereby holding the circuit of said auxiliary relay intact through the 120 branch wires 46. Should the train be traveling in the opposite direction, that is, from block E to block A, the same conditions will prevail and the auxiliary relay magnet behind the train will be maintained energized, incident to the contact levers 22 under the control of the magnets 19 engaging the back contacts 27 and holding the circuit of said auxiliary relay closed through the 125 branch wires 47.

From the above description taken in connection with the accompanying drawings, the following essential features will be noted: First, the breaking of one control circuit of a signal motor upon the deenergization of one side of the interlocking relay and the holding of such control circuit open upon the deenergization of the other side of the interlocking relay, as the train travels from block to block, incident to one of the contact levers of the last deenergized side overlapping the corresponding contact lever of the first deenergized side and holding the first lever and associated levers down irrespective of the reenergization of the first side of the interlocking relay. Second, the locking of either side of the interlocking relay by the other side, depending upon which side is released first by the corresponding magnet. Third, the opening of the auxiliary relay ahead of the train by the interlocking relays and the closing, and maintaining closed, of the auxiliary relay magnet behind the train, incident to the back contact of the interlocking relays, and fourth, the holding open of one signal motor control circuit at a siding switch, by a train approaching such switch, through the auxiliary relay, so that when the other control circuit of the motor is opened by an opposing train approaching the siding, the signal will go to danger.

While I have herein shown and described the preferred form of my invention by way of illustration, I wish it to be understood that I do not limit or confine myself to the precise details of construction herein described and delineated, as modification and variation may be made within the scope of the claims and without departing from the spirit of the invention.

I claim:

1. In a block signal system, the combination with a trackway divided into blocks and motor operated signals at the meeting ends of the blocks normally held in clear position and capable of movement to danger position, of multiple control circuits for each signal motor, and a train controlled interlocking relay controlling each set of circuits and operable to break one of said circuits upon the presence of a train in one block and to break the other of said circuits and lock the first circuit open when the train enters the next adjacent block whereby a danger signal will be left behind the train.
2. In a block signal system, the combination with a trackway divided into blocks, a siding, and siding switch points controlling communication between said trackway and siding, motor operated signals at the meeting ends of the blocks normally held in clear position and capable of movement to danger position, normally closed multiple control circuits for each motor, a train controlled interlocking relay controlling each set of said

circuits and operable by the presence of train in one block to break one of said circuits and when the train moves into the next adjacent block to break the other of said circuits and lock the first circuit open whereby the signal will be set at danger, and a remote controlled auxiliary relay controlling one of the control circuits of the set adjacent to the switch points.

3. In a block signal system, the combination with a trackway divided into blocks, siding and siding switch points controlling communication between said trackway and siding, motor operated signals at the meeting ends of the blocks normally held in clear position and capable of movement to danger position, normally closed multiple control circuits for each motor, a train controlled interlocking relay controlling each set of said circuits and operable by the presence of a train in one block to break one of said circuits and when the train moves into the next adjacent block to break the other of said circuits and lock the first circuit open whereby the signal will be set at danger, a auxiliary relay controlling the advance control circuit of the set adjacent to the switch points, and a remote controlled control circuit including said relay and extending through a predetermined number of the interlocking relays in advance of the switch points of the siding whereby the break in the control circuit under the control of said auxiliary relay may be opened by a train approaching the switch points in one direction so that a train approaching the switch points from the opposite direction will, upon breaking the other control circuit of the set adjacent to the switch points, cause the signal to go to danger.

4. In a block signal system, the combination with a trackway divided into blocks and sidings arranged along the trackway and communicating therewith, of motor controlled signals at the meeting ends of the blocks normally held in clear position and capable of movement to danger position, multiple control circuits for each motor, train controlled interlocking relays controlling the respective sets of circuits and operable by the presence of a train in one block to break one of said control circuits and when the train enters the next adjacent block to break the other of said control circuits and lock the first-mentioned circuit open, auxiliary relays controlling the advance circuits of the respective sets adjacent to the sidings, and a normally closed controlling circuit for each of said auxiliary relays extending from the particular auxiliary relay through the rear side of the interlocking relay adjacent to the other siding whereby trains approaching each other head on will receive danger signals when in the vicinity of the respective sidings.

5. In a block signal system, the combination with a trackway divided into blocks, and sidings arranged along the trackway and communicating therewith, of motor controlled signals at the meeting ends of the blocks normally held in clear position and capable of movement to danger position, multiple control circuits for each motor, train controlled interlocking relays controlling the respective sets of circuits and operable by the presence of a train in one block to break one of said control circuits and when the train enters the next adjacent block to break the other of said control circuits and lock the first-mentioned circuit open, auxiliary relays controlling the advance circuits of the respective sets adjacent to the sidings, and a normally closed controlling circuit for each of said auxiliary relays extending from the particular auxiliary relay through the remote sets of the interlocking relays interposed between the sidings and the remote side of the interlocking relay at the other siding whereby a train passing one siding and approaching the other siding may open one control circuit at such other siding and maintain the same open while approaching the siding so that an opposing train approaching the siding will receive a danger signal when in the vicinity of the siding.
6. In a block signal system, the combination with a trackway divided into blocks, and sidings arranged along the trackway and communicating therewith, of motor controlled signals at the meeting ends of the blocks normally held in clear position and capable of movement to danger position, multiple control circuits for each motor, train controlled relays controlling each set of said circuits whereby both circuits of a motor may be deenergized upon the presence of trains in adjacent controlling blocks, auxiliary relays controlling the advance control circuits of the sets adjacent to the respective sidings, and a controlling circuit for each of said auxiliary relays extending through alternate track relays back to the other siding whereby the advance control circuit adjacent to one siding may be opened by said auxiliary relay upon a train passing the other siding and approaching the first siding so that an opposing train in the vicinity of the siding having opened the other control circuit will receive a danger signal.

In testimony whereof I affix my signature.

JUDSON SHOECRAFT.
